UNITED STATES PATENT OFFICE.

WILLIAM C. BANKER, OF CHICAGO, ILLINOIS.

TOBACCO-PIPE.

1,277,826.

Specification of Letters Patent. Patented Sept. 3, 1918.

Application filed January 12, 1917. Serial No. 142,038.

To all whom it may concern:

Be it known that I, WILLIAM C. BANKER, a citizen of the United States, residing at Chicago, in the county of Cook and State 5 of Illinois, have invented certain new and useful Improvements in Tobacco-Pipes, of which the following is a specification.

This invention relates to tobacco pipes, and is particularly concerned with an im- 10 proved form of connection between the pipe stem and the mouth piece.

In the construction illustrated, I have shown a pipe stem and mouth piece in each of which are two ducts, the upper for the 15 passage of smoke, and the lower for the draining of saliva. This is the preferred construction with which my invention may be used. In attaching the mouth piece to the stem, I employ a screw threaded con- 20 nection of special construction, as will be presently pointed out. My improved pipe is easily and cheaply made, is convenient and durable, and above all provides a connection between the mouth piece and stem 25 which is secure and tight without affecting the appearance of the pipe. At the same time it insures a registration of the ends of the two ducts such as to maintain clear pas- 30 sages from the bowl to the mouth-piece. These various objects as well as others to be hereafter noted are attained by my invention which is illustrated in detail upon the accompanying drawing, showing:

In Figure 1, a longitudinal sectional view 35 through a straight pipe;

In Fig. 2, a similar view of a curved pipe, the end of the connecting stud being pointed and engaged with a plug;

In Fig. 3, a detail of the adjoining ends 40 of the mouth piece and stem, the parts being separated; and

In Fig. 4, a cross section through the pipe stem on line 4-4 of Fig. 1.

The present pipe comprises the usual 45 bowl 6, stem 7, and mouth piece 8. Extending through the stem and mouth piece are two passages 9 and 10, one preferably above the other, the upper passage 9 opening into the bowl 6. The lower passage 10 which 50 communicates with the passage 9 only at the end 11 of the mouth piece terminates at a point 12 in the bowl bottom. A plug 13 secured in place by any appropriate means—friction, threading, or otherwise—serves to 55 normally close this end of the passage 10.

In pipes of this character it is well recognized that smoke is drawn through the passage communicating with the bowl, while the other passage receives the saliva which from time to time can be cleaned out through 60 the opening 12.

It is highly desirable that the mouth piece of a pipe should be removable from the stem, and that when replaced in position it should effect a tight connection therewith. 65 In the present pipe, I use a threaded connection rather than one which depends upon friction. The threaded stud ordinarily employed for this purpose is not available with pipes of the character described (unless 70 both the stem and mouth piece be of excessive diameter) for the reason that the two ducts cannot easily be made to pass through the body of the stud. The particular form of connection devised to meet the conditions 75 noted is as follows:

A threaded stud 14 is secured centrally into the mouth piece and preferably cemented in place. This stud is of diameter practically equal to the distance between 80 the centers of the two passages 9 and 10. In order that the stud may not obstruct these passages slots 15 are arranged longitudinally of the stud through its length and located at points which will register with 85 the passages 9 and 10 in the mouth piece. As it is usual to form these passages by boring, in consequence of which the passages are round in cross section, I prefer to form the slots 15 semi-circular in shape as 90 best indicated in Fig. 4. When the stud 14 is properly secured in place within the mouth piece, the walls of the passages and slots will align so as to present no obstruction whatever. Within the proximate end 95 of the stem is a socket 16 threaded to receive the end of the stud which projects from the mouth piece. In the construction shown in Fig. 2 the projecting end of the stud is cone-shaped as at 17 and is shaped 100 to enter a cavity of similar shape, formed in a plug 18, of cork or other suitable material, positioned within the far end of the socket 16. When the mouth piece is attached to the stem in the intended manner, 105 the threads of the stud engaging within the socket will draw the parts together with a tight fit. This ultimate position of the mouth piece relative to the stem should, of course, be such that the slots 15 of the stud 110

will align with the passages 9 and 10 in the stem, so that the continuity of these ducts from end to end may be preserved, and for this purpose the stud should be adjusted 5 properly lengthwise of the mouth piece to bring the meeting ends of the mouth piece and stem into firm contact when the passages formed in these parts are exactly in alignment. Where the cork plug 18 is used, the 10 cone end of the stud should likewise engage therewith, when the passages 9 and 10 align in the mouth piece and stem, although a slight deviation is permissible due to the resilient or compressible character of the plug 15 which enables the stud to remain in engagement therewith at varying positions longitudinally of the stem.

In the present pipe, it will be seen that I have provided a tight connection between 20 the stem and mouth piece which can be simply made. The importance of having the connection tight is increased greatly in pipes of the kind shown, for the reason that leaks in both the smoke and saliva passages 25 to the pipe exterior, as well as leaks between

the passages interiorly of the pipe, should be prevented.

I claim:

In a pipe, the combination of a mouth piece, a threaded stud fixedly secured to one end of the mouth piece, and a stem arranged for threaded engagement with the stud whereby a connection is established between the stem and mouth piece, there being in the stem and mouth piece two passages whose proximate ends are adapted to align when the stem and mouth piece are in proper relative rotative position, and the stud being of such size as to partially obstruct each of said passages but being formed with slots 35 disposed longitudinally thereof in alignment with the passages in the mouth piece whereby said passages remain continuous through the stud, the threaded connection between the stud and stem being such as to insure 40 these parts lying in proper relative rotative position to preserve the continuity of the passages through the stud and stem as well, substantially as described.

WILLIAM C. BANKER.
